UNITED STATES PATENT OFFICE

166,052

BOTTLE

Frasier Smith, Wheeling, W. Va., assignor to
Hazel-Atlas Glass Company, Wheeling, W. Va.,
a corporation of West Virginia

Application October 31, 1951, Serial No. 17,179

Term of patent 7 years

(Cl. D58—6)

To all whom it may concern:

Be it known that I, Frasier Smith, a citizen of the United States, residing at Wheeling, in the county of Ohio and State of West Virginia, have invented a new, original, and ornamental Design for a Bottle, of which the following is a specification, reference being had to the accompanying drawing, forming part thereof.

Figure 1 is a perspective view of a bottle, showing my new design;

Figure 2 is a top plan view thereof; and

Figure 3 is an elevational view thereof.

I claim:

The ornamental design for a bottle, as shown.

FRASIER SMITH.
